UNITED STATES PATENT OFFICE.

MICHAEL RINEHARDT VINSON, OF WALDO, ARKANSAS.

DESIGN FOR A WEEDING-HOE.

SPECIFICATION forming part of Design No. 29,389, dated September 20, 1898.

Application filed July 15, 1898. Serial No. 686,039. Term of patent 7 years.

To all whom it may concern:

Be it known that I, MICHAEL RINEHARDT VINSON, a citizen of the United States, residing at Waldo, in the county of Columbia and State of Arkansas, have invented and produced a new and original Design for a Weeding-Hoe; and I do declare the following to be a full, clear, and exact description of the same, reference being had to the accompanying drawings, forming a part thereof.

Figure 1 is a face perspective view of my weeding-hoe, showing my new design. Fig. 2 is a rear perspective view, and Fig. 3 is a sectional view taken on the line XX of Fig. 1.

As shown in the drawings, the leading or material feature of my design consists of a weeding-hoe having an eye 1, brace 2, and cutting-flanges 3, which are integral with each

side of the hoe-blade, starting from the top of the same and running about two-thirds down the length of its sides and setting back at an angle of nearly ninety degrees. The blade 4 broadens from its top to its bottom until its lower corners 5 are on a line beyond the extreme edges of the cutting-flanges 3.

Having described my invention, what I claim as new, and desire to obtain by Letters Patent, is—

The design for a weeding - hoe as herein shown and described.

In testimony whereof I affix my signature in presence of two witnesses.

MICHAEL RINEHARDT VINSON.
